HANDLE BAIL AND HANDLE SPRING MEANS
FOR CARPET SWEEPERSFred W. Pullen, Grand Rapids, Mich., assignor to
Bissell Carpet Sweeper Co., Grand Rapids,
Mich.

Application January 15, 1932. Serial No. 586,716

2 Claims. (Cl. 15—41)

The objects of this invention are:

First, to provide a very simple and compact construction in which the springs are retained under tension and consequently effectively supported in place.

Second, to provide an improved construction of nib and spring connection.

Third, to provide improved means of effectively retaining the pivot connection while at the same time permitting the necessary movement for the proper manipulation of the handle.

Further objects and objects pertaining to economies of construction will definitely appear from the description to follow.

15 A preferred embodiment of my invention is illustrated in the accompanying drawing, in which:

Fig. 1 is an end elevation view of a carpet sweeper case with my improved bail and spring structure in place, the brush and end bar and driving means being removed so that the detailed construction will fully appear.

20 Fig. 2 is an enlarged detail vertical sectional elevation, the parts being shown in broken section on line 2—2 of Figs. 1, 3 and 4.

Fig. 3 is an enlarged detail sectional elevation taken on line 3—3 of Fig. 2 showing details of the pivot and retaining means.

25 Fig. 4 is an inverted sectional plan view taken on line 4—4 of Figs. 1 and 2, showing details of centering arrangement for the said bail.

Fig. 5 is a similar central sectional view showing the action of the bail when the handle is tipped.

Fig. 6 is a detail end elevation view showing a 30 slightly modified construction with the centering stops above the pivots in place of below.

Fig. 7 is a slight modification of the spring connection.

The parts will be identified by their numerals 40 of reference which are the same in all the views.

1 is the end of the carpet sweeper case. 2 is the bail. 3 are the pivot nibs with necks 31, pivoting in apertures 4 in the end of the case. To one bail member 21 is secured the cross spring clip 5.

45 6, 6 are the handle springs, bowed upwardly and outwardly and extended downwardly. The end 61 of each spring is driven into the wood of the end of the case and is inclined downwardly at an angle of about eighty degrees. This serves to 50 balance the sweeper handle and avoids the tipping action that occurs when it is not present.

Each pivot nib 3 is retained by plate 7 through which it is inserted and the annular neck 31 is engaged by the side of the aperture 73 in the plate 55 7, as seen in Figs. 2 and 3. The plate 7 is retained

by screws 71, see Fig. 2, and has rounded stops 72 formed by indenting the plate. It will thus be seen that the pivot cannot be withdrawn without detaching the plate.

In the preferred construction, the bow end of 60 the bail projects downwardly at 22 between stops 72 on the retainer plate 7. The yielding of the bail thus provides in effect a yielding stop which assists in holding the handle in central position when it is at rest. It can be swung down to either 65 side when the carpet sweeper is in use and does not interfere with the free pivoting.

In Fig. 6, I show the projections at 74 above the pivot center. While they serve the same purpose, it is not necessary, of course, to provide an ex- 70 tension on the bail in this structure.

In Fig. 7 I show the spring 6 as it appears when connected to a case with a sheet metal end 101, simply perforated at 102.

I desire to claim the particular details of the 75 construction and also to claim the invention broadly as pointed out in the appended claims.

Having thus described my invention, what I 80 claim as new and desire to secure by Letters Patent is:

1. In a carpet sweeper structure, the combination of a case, a bail therefor, a pivot nib at right angles to the said bail end and pivoting in an aperture in the said case, the said nib being formed with a reduced neck, and a retainer plate 85 fastened to the face of the case and having an aperture for the insertion of the said pivot nib, the aperture in the plate being offset from the aperture in the case to engage the said neck and retain the pivot nib in the said case. 90

2. In a carpet sweeper structure, the combination of a case, a bail therefor, a pivot nib at right angles to the said bail end and pivoting in an aperture in the said case, a spring clip having laterally projecting ears carried by said bail end, 95 and upwardly and outwardly and downwardly formed handle springs having lateral downwardly inclined ends inserted in the face of the end of the body of the said case.
